[57] CLAIM

The ornamental design for a plant support system, as shown and described.

DESCRIPTION

FIG. 1 is a perspective view of a plant support system embodying the present invention;

FIG. 2 is a perspective view of a modified arrangement of the plant support system shown in FIG. 1 in an expanded and adjusted position; and,

FIG. 3 is a top plan view of the plant support system shown in FIG. 1.

The portion of the ground into which the end portions of the support posts are inserted, shown in broken dotted lines is are not intended to be part of the claimed invention.

The broken line showing of ground cover in FIGS. 1 and 2 is for illustrative purposes only and forms no part of the claimed design.
